CLAIM

The ornamental design for a paper sheet, as shown and described.

DESCRIPTION

FIG. 1 is a top plan view of a paper sheet showing our new ornamental design;

FIG. 2 is a reference view of the paper sheet of FIG. 1;
FIG. 3 is an enlarged top plan detail view of the area circumscribed within FIG. 2;

FIG. 4 is a cross-sectional detail view in the direction of cut line 4-4; and,

FIG. 5 is a cross-sectional detail view in the direction of cut line 5-5.

The dash-dash broken lines in FIG. 1 depict the boundary of the claim and form no part thereof. The dash-dash broken lines present in FIG. 2 illustrate the area of the enlarged detail view shown in FIG. 3, as well as the cut lines for the detailed cross sectional views shown in FIGS. 4 and 5, and form no part of the claimed design. The dot-dash broken lines present in FIG. 2 depict the boundary of the claim and form no part thereof. The dot-dash lines present in FIG. 3 depict the border of the enlarged detail view, taken from FIG. 2, and form no part of the claimed design. The dash-dash broken lines of FIGS. 4 and 5 illustrate portions of the article and form no part of the claimed design.
